UNITED STATES PATENT OFFICE.

HENRY H. GORRINGE AND AXEL O. TENGVALL, OF NEW YORK, N. Y.

HYDRAULIC EJECTOR.

SPECIFICATION forming part of Letters Patent No. 314,237, dated March 24, 1885.

Application filed December 29, 1884. (No model.)

To all whom it may concern:

Be it known that we, HENRY H. GORRINGE and AXEL O. TENGVALL, both residing in the city of New York, N. Y., have invented an improvement in High-Pressure Hydraulic Ejectors; and we do hereby declare that the following is a full, clear, and exact description of the invention, which will enable others skilled in the art to which it appertains to make and use the same.

The object of our invention is to provide high-pressure hydraulic ejectors with a simple, reliable, self-adjusting attachment which will effectually prevent the pressure in the high-pressure pipe from being communicated to the low-pressure pipe or create an excessive pressure in the discharge pipe or hose. We attain this object by the mechanism illustrated in the accompanying drawing, which represents a vertical section of the entire machine.

The passage A communicates with the high-pressure pipe, the passage B with the low-pressure pipe, and the passage C with the discharge pipe or hose. Through the passage D the pressure existing in A is communicated to the smaller piston E. Through a similar passage, F, the pressure in C is communicated to the larger piston G. By turning the handle H the cone-valve I is opened and the ejector put in operation. The pressure on the piston

E keeps the cone-valve open until the pressure in C rises above the desired limit, when the pressure on the piston G will become greater than that on the piston E and the cone-valve will begin to close, thus reducing the opening for high-pressure water, and decreasing the flow and consequently the pressure at C. The nut K is left free to slide up and down in the guide-bracket L.

We are aware that hydraulic ejectors have been described, made, and used for many years, and that self-adjusting devices for hydraulic ejectors have been patented.

What we claim as our invention, and desire to secure by Letters Patent, is—

A hydraulic ejector in which the pressures in the discharge-pipe and high-pressure pipe are communicated to pistons having areas proportioned so as to adjust the flow of high-pressure water automatically, substantially as and for the purpose herein set forth.

In testimony whereof we have hereunto signed our names in the presence of two subscribing witnesses.

HENRY H. GORRINGE.
AXEL O. TENGVALL.

In presence of—

WM. D. LEONARD,
G. A. STIMPSON.
